Mary Hermanski INVENTOR

BY Victor J. Evans

ATTORNEY

UNITED STATES PATENT OFFICE

MARY HERMANSKI, OF GARBER, OKLAHOMA

GARMENT

Application filed December 2, 1930. Serial No. 499,547.

My present invention relates to union suits, and my object is the provision of a closed seat garment which will be well-fitting and comfortable and which is open along its 5 sides from the waist line to the ends of the legs, the garment having stitched in the openings thus provided the edges and the top of substantially rectangular sheets of the same material from which the garment 10 is formed and which sheets or strips are folded upon themselves to provide two connected cross sectionally substantially V-shaped portions, the central portion at the outer edge thereof having attached to its 15 lower end a button and the inner portions, at the sides of their connections with the said legs being provided with openings to receive the buttons therethrough and whereby when the sheet is folded inwardly of and 20 buttoned to the legs the garment presents a neat and attractive position and when the buttons are released and the folds of the sheet brought outwardly therefrom the legs are materially widened for sanitary or other 25 purposes.

A practical embodiment of the invention is represented in the accompanying drawings forming a part of this specification, in which:

Figure 4 is a similar sectional view but 35 looking toward the opposite leg and showing the filler sheet or strip disconnected from the leg proper.

The union suit 1 has short legs 2. The suit is preferably provided with an open 40 front extending from the crotch to its neck portion, one of the edges of the front overlying the other and the lapping edges being connected together by the usual buttons 3.

From its waist to the outer ends of the 45 short legs 2 the garment 1, from the sides thereof, is slitted or open, and to the edges of the said open portion there are stitched or otherwise secured the edges of a sheet or strip of the same material as that of the garment. The stitched edges of the sheet or 50 strip 4 are provided with button holes and the said button holes 5 pass through the divided sides of the legs 2. The sheet or strip 4, when arranged in the legs 2, is folded to provide side members 6 disposed adjacent to 55 the sides of the legs 2, the side members having their inner ends folded to provide the inner extensions 7 which are of the same length as the sides 5. The outer ends of the inner portions 7 of the strip or sheet are, 60 of course, connected and thus the pair of folds comprising the inner members 7 are substantially V-shaped in cross section, and the outer ends of this portion 7, adjacent to the bottom of the sheet, have attached thereto 65 a button 8 designed to be passed through the button holes 5 when the plaited or folded sheet is to be secured to the legs to close the open portion of the legs 2 of the garment. The fabric sheets have their upper edges 70 stitched, as at 9, to the waist line and at the divided leg portions of the garment.

The construction and advantages of my improvement will, it is thought, be understood and appreciated by those skilled in the 75 art to which the invention relates after the foregoing description has been carefully read in connection with the accompanying drawings.

Having described the invention, I claim:

A union suit of the character described which is provided with short legs and the said garment, from the waist line to the outer ends of the legs having its sides divided, a fabric sheet of substantially rectangular formation having its upper end stitched to the waist line at the dividing portion of the garment and having its edges stitched to the divided portion of the legs of the garment, said sheet designed to be folded into the legs 80 85 90 95 of the garment or to be spread outwardly therefrom and when folded to provide sides and inner portions connecting the sides, the said inner portions being thus of cross sectionally V-shaped formation, the outer and connecting portion of the center, adjacent to the lower end thereof, having a button and the sides of the fold and the sides of the divided legs having button holes to receive the button therethrough.

10 In testimony whereof I affix my signature.
MARY HERMANSKI.
